METHOD OF EXPRESSING OIL

Frederick W. Weigel, Fairview Village, Ohio, assignor, by mesne assignments, to The V. D. Anderson Company, Cleveland, Ohio, a corporation of Ohio

Continuation of application Serial No. 389,207, April 18, 1941. This application November 5, 1943, Serial No. 509,037

6. Claims. (Cl. 260—412.2)

1

This invention relates to the recovery of oil from oil bearing proteinaceous material, particularly of vegetable origin, such as oil bearing seeds, nuts or the like. While more particularly applicable to the treatment of many kinds of oil bearing proteinaceous materials, such as various nuts, seeds and the like, it will be more particularly described with reference to flaxseed and soy beans. Under some circumstances the invention also may be applicable for use in the removal of oil from proteinaceous materials of animal origin.

More particularly the invention aims to provide an improved process which may be performed in a single unit including all the necessary apparatus and devices for recovering oil from the material being worked upon in such manner that said material is introduced into the apparatus as a more or less continuous stream and is caused to flow through it under motion at all times, while it is subjected in order to those steps which first convert the proteinaceous material into suitable and appropriate condition for expression of oil therefrom, followed by the actual oil expressing step so as to discharge from the apparatus the relatively dry hard cake on the one hand and a high quality oil of maximum quantity on the other hand. Thus by this process, the various steps to which the material is subjected are conducted not discontinuously in separate machines or devices, but continuously and in order without time or space gaps between them, with the result not only of conserving heat and avoiding cooling and delay such as might impair the quality of the product, but also retaining unharmed the maximum quantity of high grade oil.

Another object is to provide an improved method of oil recovery from proteinaceous material, which consists in performing the heating or cooking operation upon a large mass of raw material, many times greater than the quantity being expressed at any moment, the operation being completed at a temperature definitely and materially below the optimum temperature for expressing, but carried out for an extended period of time, much longer than heretofore employed, and then rapidly and immediately conditioning the raw material, in smaller quantities, with a rise in temperature to the optimum temperature for expressing, followed by immediate continuous expression in a press, all to the end of securing maximum oil output without impairment of quality.

Further objects of the invention are in part obvious and in part will appear more in detail hereinafter.

This application is a continuation of my prior application for Method and Apparatus for Expressing Oil, filed April 18, 1941, Serial No.

2

389,207, now abandoned, to which reference may be had if desirable or necessary.

In the drawings, which represent one suitable embodiment of the invention, Fig. 1 is a side elevation of the entire apparatus, portions being broken out and in section to expose interior parts; Fig. 2 is an end view from the left in Fig. 1; Figs. 3, 4 and 5 are detail views illustrating one of the variable feeders, Figs. 3 and 4 being views along similarly numbered lines of Fig. 2, and Fig. 5 being a view along the line 5—5 of Fig. 4; while Fig. 6 is a fragmental sectional view taken along the line 6—6 of Fig. 1.

Heretofore, in the extraction or recovery of oil from proteinaceous materials, either of vegetable or animal origin, such, for example, as cottonseed, flaxseed, copra, soy beans or the like, it has been customary first to heat or cook the material in relatively finely divided form, either as whole seeds when they are small, or suitably comminuted when of larger size, in a suitable apparatus heated by steam or otherwise and in which, in the presence of moisture, the material not only is sterilized, but the enzymes, starches, and other ingredients are or may be decomposed or modified in such manner as to disrupt the oil bearing cells and release the oil, but without harmful effect upon it. The heating or cooking process may be conducted either by a batch process, or may be more or less continuous. But, in either event, the product of the heating apparatus, as it issues therefrom, is conducted or conveyed, usually over some distance, to other apparatus, such as a drier or conditioner. During its travel thereto heat is lost. Because the quantity of material in the vessel is relatively small and to counteract the contemplated heat loss, the cooking temperature has always been relatively high, and usually appreciably above the optimum temperature for expressing, entailing ultimate loss in quantity and quality of the oil product. In the drier, moisture is permitted or caused to escape and upon discharge from the drier the material is again conducted or conveyed, again over an appreciable distance, to a conditioner or to a suitable oil expelling press. In either case the transfer again requires and is at the expense of reduction of temperature and loss of heat, with further delay entailing additional deterioration of the product.

According to the present invention I subject the material from which oil is to be extracted, in a large mass, to a heating or cooking operation in the closed chamber of a vessel vented to atmosphere if necessary for escape of moisture. The vessel is so arranged as to permit the operation to be carried out at a temperature and for a period of time and under conditions conducive to the most efficient results, often involving expulsion of some of the moisture in the ma-

terial in the form of water vapor, but usually with thorough cooking over a long period of time so as to fully expand the oil cells and free the oil for extraction.

Generally speaking, proteinaceous materials of the kind here involved, such as seeds and nuts, are variously subjected, according to their kind, to one of three or more separate and distinct modes of treatment, as follows:

The first group of materials requires cooking under very moist conditions, followed by drying to reduce the moisture content to an optimum value, say 3%. Accordingly, the heating or cooking vessel is usually vented to atmosphere through a relatively small vent designed to prevent material loss of moisture from the cooking vessel. Most of the moisture is taken out or permitted to escape later as the material passes through the conditioner. However, the cooking operation is best performed at a temperature below the optimum final temperature for pressing, to avoid harming the oil by too harsh treatment. These materials, accordingly, are subjected to a cooking process for an extended period of time, say 45 to 60 minutes, at a maximum temperature of about 225° F. at the discharge outlet. In the conditioner escape of moisture is permitted at a controlled rate, and the temperature is permitted to rise, so that in a period of from 7 to 15 minutes, its moisture content has been reduced to 3% when it reaches the optimum final pressing temperature of 235° F.

The materials treated according to this first plan include, for example, cottonseed, whole or decorticated, flaxseed, and rape seed. However, with flaxseed and rape seed the maximum cooking temperature is usually 200° F. and the optimum final pressing temperature 210° F.

The second group of materials does not require the same kind of cooking, in the ordinary sense of the word, as does cottonseed. Here the cooking process, more accurately described, is more on the order of drying, mainly for the purpose of reducing the moisture content. But it must be conducted carefully, without damage to the material. Accordingly, in the heating or cooking vessel, the material is subjected to a gradual increase in temperature up to a maximum definitely and materially below the optimum pressing temperature and for a time which varies with the initial moisture content of the material. For example,

(a) Soya beans are treated to reduce the moisture content to about 3%. They are heated in the cooker for from 20 to 60 minutes to a maximum temperature of 260° F. In the conditioner the temperature is permitted to rise to 270° F., the optimum temperature for pressing.

(b) Decorticated peanuts are similarly dried in the cooker to reduce the moisture content to approximately 2.5%. They are thus treated for from 20 to 60 minutes at a maximum temperature of 225° F., and in the conditioner the temperature is permitted to reach the optimum pressing temperature of 235° F.

(c) Copra, palm kernels, babassu nuts, tucum nuts, Brazil nuts, coquita nuts and muru-muru nuts are dried to a moisture content of about 2%, the heating process continuing for from 20 to 60 minutes at a maximum temperature varying from 190° to 200° F. In the conditioner, the temperature is permitted to rise to the optimum pressing temperature of from 215° to 220° F.

The third group of materials includes, for example, tung nuts, castor beans, and sesame seed.

These materials are treated in the heating vessel under closed conditions (air excluded) to reduce the moisture content, the time of treatment varying with the initial moisture content.

Tung nuts are heated for from 20 to 60 minutes up to a maximum of 200° F. to reduce the moisture content to 3%, and in the conditioner the temperature is permitted to rise to 210° F., the optimum final pressing temperature.

Castor beans are dried for from 20 to 60 minutes at a temperature of 180° F. to permit the moisture content to be reduced to 4% and in the conditioner the temperature is permitted to rise to 190° F.

Sesame seed are heated for from 20 to 60 minutes at 200° F. to reduce the moisture content to 3%, and in the conditioner the temperature is permitted to rise to 210°.

The cooking vessel is of sufficient size to hold a large quantity of material in a single mass which is kept thoroughly mixed so that it is fairly homogeneous. The temperature and moisture of this single large mass are readily controlled, the former being definitely below the optimum expressing temperature, and the latter above its final value. Inflow and outflow of material are also controlled, and are at a rate, in pounds per minute, comparable to the rate of later flow of material through the press, but small as compared with cooker capacity.

Promptly upon conclusion of the heating or cooking operation and without loss of either time or temperature, and in a relatively short time, the product of the first heating operation is subjected to a conditioning step for a suitable period of time during which moisture may be expelled to reduce the moisture content and to stabilize it at the optimum value for the particular material at the time of expression. At the same time, the temperature is carefully controlled so that the product leaving the conditioner is at the optimum temperature for expressing the oil. This, of course, involves a gradual rise in temperature as the material passes through the conditioner. But the conditioner is of small capacity as compared with the cooker so that the time of heating at the increased temperature is relatively short. The material is withdrawn from or is permitted to leave the heating or cooking vessel continuously only in small amounts and is immediately passed through the conditioning vessel keeping it thoroughly mixed. It results from this conditioning treatment that the smaller amounts of material drawn from the mass in the cooking vessel are made more completely homogeneous and are given a final treatment closely controlled as to moisture and temperature so that optimum conditions of temperature and moisture content exist at the moment the product leaves the conditioning vessel and passes into the press. In other words, in this conditioner the material is subjected, immediately after cooking, to suitable treatment, in the minimum time, which modifies its condition to that determined to be most desirable from the standpoint of both temperature and moisture content.

Thereupon, again promptly and without delay, the material is introduced into a press of suitable form, preferably a continuous press, as will appear. In said press, without interruption of its movement and without loss of temperature, the material is subjected to increasing pressure to expel the oil therefrom so that it issues from the press in the form of thin hard frag-

ments of relatively dry cake; on the one hand, and a high grade oil of maximum quantity on the other hand.

The entire process is conducted without material travel of the substance being worked upon as it proceeds from step to step of the process or from element to element of the apparatus, so that no time is available for deterioration or for loss of heat and the entire process is carried on at minimum expense.

Referring now to the drawings, 1 indicates a continuously operating high pressure screw press which may be of any suitable form for the purpose and the details of which are more or less immaterial. For example, said press may be of the general form illustrated and described in a prior Patent No. 1,971,632 for Feeding Mechanism for Presses, granted August 28, 1934, to Raymond T. Anderson, to which reference may be had if desirable or necessary. Said press comprises a horizontally disposed main press, marked generally 2, to which material is supplied from the vertical feed press 3 supplied by a feed chute 4 communicating directly with the discharge end of a conditioner 5. Material is fed at a controlled rate into the conditioner 5 from the cooker 6. All parts of the mechanism, including the cooker 6, conditioner 5, and press 1 are organized in cooperative relation so that the material to be treated travels therethrough continuously, without stopping, and during its travel it is properly cooked, conditioned, and then pressed to separate the oil from the cake.

The material to be treated is supplied from a bin or hopper, shown conventionally at 7, to a variable feeder 8, of known construction, including a trough 9 in which rotates a feed screw 10, one end of which underlies the outlet from hopper 7 and the other end of which discharges through a conduit 11 into the chamber of a vessel 6. The feed screw is actuated in any suitable manner, such as by a sprocket chain 12 driving adjustable and variable mechanism, marked generally 13, the purpose of which is to vary the rate of rotation of the feed screw or worm and consequently the amount of material fed to the vessel 6 during a given period of time. The details of the variable feeder form no part of this invention and therefore require no further description.

The vessel 6, here referred to, for convenience, and not in any sense of limitation, as a cooker, is a large, generally cylindrical vessel, double walled to provide an annular jacket or chamber 14 through which steam may be circulated for heating purposes. It is mounted generally above the press 1, to conserve space, although one end may extend beyond the press where it is supported from the floor by suitable legs or a frame 15.

Within the treating chamber 16 is located a combined agitator and conveyor, which generally speaking comprises a central shaft 17 and two sets of helical blades 18, 19 mounted upon said shaft to turn therewith, the edges of the blades travelling fairly close to the surface of the inner wall 20 of the cooker. This agitator and conveyor may be generally of the form illustrated, described and claimed in my Patent No. 2,227,522 for Combined Agitator and Conveyor Mechanism, granted January 7, 1941, to which reference may be had for a more complete description if desirable or necessary. For the purpose of this application it is sufficient to say that the direction of spirality of twist of the two sets of

blades 18, 19 is opposed. The blades 18, for example, may be right-handed and the blades 19 left-handed, or vice versa, and one set of said blades, such as the blades 18, are slightly longer than the blades of the other set 19. The result of this construction is that upon rotation of shaft 17 in the proper direction the material within the vessel is very thoroughly agitated or turned over, all of it being kept continuously in motion, with gradual feed of the material progressively from the supply toward the discharge end.

The vessel 6, as a whole, is of relatively large diameter, say thirty-six inches, more or less, and of any suitable length, up to as much as ten or twelve feet. It therefore will accept and hold a rather large quantity of material undergoing treatment, either heating or cooking, sufficient, for example, to keep the press 1 in operation for one or two hours. However, the actual amount of material within the cooker at any one time may be varied and will vary in accordance with the desired results and the character of the material being operated upon, as will more fully appear. In each case, however, a large quantity of material is held in one fairly homogeneous mass during the cooking operation.

Preferably the chamber 16 is openly vented to the atmosphere, as by one or more vent outlets 21 each provided with adjustable operating mechanism (like that shown in Fig. 6) for its hinged door 23, and if desired one or more of said vents may communicate with a vent stack 22 leading outside of the building, as shown at the left-hand vent, Fig. 1. A slide damper 22a controls this vent opening. By way of these vents the steam, water vapor and gases generated during the cooking operation and originating in the moisture and other substances within the material being operated upon may be allowed to escape to atmosphere, and the cooking operation proceeds substantially at atmospheric pressure, as will be readily understood. But the vents obviously may be more or less closed when moisture escape should be reduced or prevented.

At the discharge end of the cooker, its treating chamber communicates by way of a nozzle 24 with a variable feeder 25 of the same form as the one at the inlet end of the cooker, said variable feeder communicating by a nozzle 26 with the supply end of the conditioner 5. Since the variable feeder 25 is of the same form as the feeder 8, it requires no special description. The feeder 25 is as short as possible, of the order of a few feet, so that practically no time or temperature is lost there.

It should be noted, however, that the feeders 8 and 25, according to how they are adjusted, absolutely control the rates of inflow of material to and outflow from the vessel 6, regardless of the quantity in its chamber, although it is also true, as will appear, that these feeders may be so operated as to initially determine, and then maintain or vary, the quantity of material in the vessel.

The conditioner vessel 5, generally speaking, is of the same form as the cooker 6, but of reduced diameter, having a steam jacket including the annular chamber 27 through which steam may be circulated for heating purposes. Within the chamber 28 of the conditioner is located agitator and conveyor mechanism, marked generally 29, of the same form as that shown in the cooker, but of course of a diameter and with blades properly proportioned in accordance with the diameter of the conditioning chamber. Condi-

tioner 5 may also be provided with one or more vents 30 each provided with a door 31 which has an operating mechanism 32 as shown in Fig. 6. If desired, as shown in Fig. 1 toward the left end of vessel 5, a vent stack 22' may lead from the conditioner vessel to atmosphere. This vent may be controlled by butterfly damper 51. By opening either or both of said vents steam, vapors and gases may be permitted to escape at a controlled rate, as will be readily apparent.

As a general rule each of the variable feeder mechanisms is provided with a star wheel, marked generally 33. This star wheel rotates on an axis transverse to that of the worm shaft, with one side of the star wheel extending into the feeding chamber, so that the lobes thereof engage or intermesh with the worm flight, to be driven thereby. The star wheel therefore serves as an abutment to prevent rotation of the material with the worm, while traveling through the feeder mechanism, compelling it to move along therein.

Any suitable driving mechanism may be employed for the various instrumentalities described. As illustrated, the horizontal main press 2 is operated by an electric motor 34 through speed reducing gearing marked generally 35. Said motor also drives a sprocket 36 connected by a chain 37 to a sprocket 38 which, through gearing enclosed within the casing 39, operates the shaft of the vertical feeding press 3. The shaft 17 of the agitator projects from one end of the vessel and is provided with a sprocket 40 connected by a driving chain 41 to a sprocket on the shaft of motor 42. Another sprocket 43 on shaft 17 is connected by a chain 44 to a sprocket 45 on a back shaft 46 arranged to drive the variable operating mechanism 47 for the variable feeder 25 (see Fig. 2). At the other end of the vessel 6, shaft 17 is provided with a sprocket 48 over which travels the driving chain 12 for the variable driving mechanism of the variable feeder 8.

The shaft 29 of the agitator for the conditioner 5 may be provided with a sprocket 49 connected by a chain 50 to a sprocket on the shaft of motor 42.

With this arrangement the oil bearing proteinaceous materials described may be subjected to various treatments, each material according to its kind and the results desired. Whatever is the material or its treatment, it is of course obvious that the material fed, both through the cooker and through the conditioner, per unit of time, must be that quantity of material which the press 1 can properly treat in the same unit of time. But, by varying the speed of rotation of the agitator shaft 17 of the cooker, and the shaft 29 of the conditioner, as by adjusting the size of their respective driving sprockets, the rate of agitation of the material in either or both of the cooker and conditioner may be varied. Again, the quantity of material with which the cooker or the conditioner is loaded at any instant may be varied. For example, referring to vessel 6, by holding the variable feeder 25 at its outlet stationary, or by reducing its speed, while permitting the variable feeder 8 at its inlet to operate, the quantity of material within the vessel may be built up or increased to any desired degree. It may be one-tenth full, one-third, one-half or even up to two-thirds full or more. Obviously, by operating the two variable feeders 8, 25 at the same speed, the quantity of material within the cooker is maintained substantially uniform, although while the apparatus is operat-

ing the material within the cooker is gradually progressing from its inlet end to its outlet end, where it is delivered to the conditioner.

The total capacity of a heating or cooking vessel 3 feet in diameter and 12 feet long, in pounds, depends of course upon the density of the particular material being worked upon, which may weigh from 20 to 40 pounds per cubic foot, or thereabouts. A fair load of average material, with the cooker $\frac{2}{3}$ full may weigh 1500 pounds or more, many times the weight of the material actually in the press at any moment, which may run, for example, from 20 to 30 pounds.

Within the cooker the material being treated is subjected to the effect of the heat of the steam within its jacket. That heat produces a progressive action, with the conversion of moisture into water vapor or steam and with the usual effects, at the temperature employed, upon all the various substances of which the oil bearing proteinaceous material is composed, all tending to expand or open up the oil containing cells and to free the oil therefrom. Steam, water vapor and gases arise and are or may be vented through the outlets 21 if necessary. The operation proceeds slowly, in accordance with the adjustment of the parts, and it may take from 30 to 90 minutes for the material to pass clear through the cooker.

For example, in a continuous press of the kind here employed, the material passes through the press in one or two minutes or a little more. Assuming press capacity at 30 pounds, and a pressing time of two minutes, and neglecting loss of moisture, this means that material must be fed to the press, and must also be fed to and leave the cooker and conditioner roughly at the rate of 15 pounds per minute. If the charge in the cooker weighs 1500 pounds, on the average it will take 100 minutes for any given material to pass through the cooker. The time through the conditioner is considerably less because its agitator shaft turns rapidly and no attempt is made to hold the material there. It flows freely to the press.

At the outlet end of the cooker the material is released or permitted to leave, at a controlled rate, by the variable feeder 25 by which it is conveyed to and delivered into the conditioner 5, but without material loss of heat and without delay, so that the material undergoing treatment is afforded no opportunity for deterioration. In the conditioner the material is treated for a period of time shorter than its time period in the cooker, because its agitator shaft rotates rapidly and outflow is not impeded. Here the material is tempered as to its condition, progressing along toward the far end of the conditioner for whatever period of time may be suitable. In the conditioner such further emission and venting of steam vapors and gases is permitted as may be desirable. Thus the material, when it reaches the outlet end of the conditioner is in prime condition for the expressing or oil expelling operation. It is promptly delivered into the press, at the upper end of the vertical feed press thereof, and it travels down through the feed press and then through the main press, with progressive and continuous expulsion of oil, while traveling through the press, so that at the far end of the press a substantially oil-free cake is discharged.

Means is provided for carefully controlling the temperature in the vessel 6. The steam supply at 52, Fig. 1, under the control of a shut-off valve

53 passes through a pressure regulator 54 to a control valve 55. This valve is of a well known type, the position of which is controlled by means of a diaphragm in a chamber 56 which communicates by conduit 57 with a temperature sensitive Sylphon bellows, not shown, in the cooker 6. As will be readily understood, an increase of temperature in the cooker 6 beyond a predetermined point selected will cause pressure in conduit 57 to close valve 55, thus cutting off the steam entering jacket 14 through conduit 59. Upon cooling of the Sylphon bellows, steam is again admitted to the jacket and thus the temperature of cooker 6 is controlled within fairly narrow limits. The condensate from jacket 14 is drained at the point 14a.

In a similar manner means is provided for controlling the temperature in the conditioner 5. Parts similar to those just described carry out similar functions and have been given the same reference characters with a prime suffix. The drain from the conditioner jacket 27 is at the point 27a. Thus the temperature in the conditioner is also closely controlled and in fact may be given a finer regulation than that possible in the cooker 6 because of the smaller amount of material and the smaller chamber involved. To get the best results I prefer to hold the temperature at the discharge end of the conditioner within 2° or 3° F. of the predetermined point, to wit the optimum temperature for expressing of the material being treated.

It should be understood that each of the various proteinaceous materials commonly treated according to this process has its own more or less definite and well known optimum temperature at which the expressing operation should be conducted. The "optimum" temperature here referred to takes into consideration only quantity and quality of the product, neglecting cost and selling prices for oil, or other economic factors, such as labor, transportation, cost of equipment, operating costs, etc. Expression at temperatures above or below this optimum temperature entails either impairment of the quality or reduction in the quantity of the expressed oil. These optimum temperatures vary for different materials. Characteristic optimum temperatures for certain materials have been mentioned above.

Likewise, the matter of optimum moisture content, at the time of expression, is well understood in the art. It varies for different materials, and values for some materials are also given above. "Optimum" moisture content also has reference here only to quantity and quality of oil product, possibly the most important function of the conditioner is to stabilize the moisture content at the "optimum" value for expressing, usually by removing moisture, as will be readily understood.

Accordingly, in the operation of my process and apparatus, it must be assumed, that, for the particular material being worked upon, the optimum moisture content and temperature at the time of expression are known, and the apparatus is set up or adjusted accordingly. That is to say, the vents permitting escape of moisture from the heater or cooker and from the conditioner are adjusted to permit escape of moisture at a controlled rate, so that when the material passes from the conditioner to the press its moisture content is at the optimum value. Likewise, the heat applied to the cooker and to the conditioner, such as steam heat, is controlled usually thermostatically, as described, to produce and maintain independently, in each of the cooker and condi-

tioner, temperatures appropriate to the material. That is to say, the maximum temperature to which the material is subjected in the cooker is set at a value materially lower than the optimum temperature for the material, say 10° F. less, and in the conditioner the temperature is permitted to rise to the said optimum temperature or thereabouts. The operator usually takes into consideration variations in temperature such as might occur in the operation of the press at high pressure with the material subjected to great friction, and with the press cooled by a cooling fluid as is usual.

The operation of my improved process when treating flaxseed is as follows: With the feeder 25 at rest, the feeder 8 is operated to feed the flaxseed into the cooker 6 until it contains approximately one thousand pounds or more. The shaft 17 operates at approximately 30 R. P. M. and the flaxseed is retained in the cooker 6 for approximately an hour at a maximum temperature of about 200° F. A small amount of moisture is allowed to escape through the vents 24. When the desired amount of material has been accumulated in the cooker 6 the feeder 25 is started to remove a continuous small stream of material from the cooker at about the same rate as the material enters through the feeder 8. This smaller quantity of material passes directly into the conditioner vessel 5 whose mixer shaft is traveling at approximately 30 R. P. M. and this material is held at a maximum temperature of approximately 210° F. at the outlet end thereof. The material is in the conditioner vessel between 7 and 15 minutes. Entering the conditioner with a moisture of 6 or 7 per cent, sufficient moisture is permitted to escape from the conditioner vessel so that when the material passes to the feeder chute 4 the moisture content is stabilized at 3 or 4 per cent. It results from this treatment that a greater quantity of high grade oil is secured than by other known processes. I believe this to be due to the cooking of the material for a comparatively long time in a comparatively large mass at a temperature below the optimum temperature for the material, combined with the transfer of this material quickly and without appreciable loss of temperature to the conditioner where a smaller mass of material is quickly rendered completely homogeneous and its temperature and moisture are given a final stabilizing control. The material then passes directly and without loss of temperature to the expeller press where the temperature is controlled in a known manner, preferably by passing cooling oil over the barrels of the presses 2 and 3 so as to dispel any excess temperature generated by the friction and compression.

The process is similar for soy beans except that a temperature of approximately 260° F. is maintained in the cooker and the optimum temperature of approximately 270° F. is maintained at the discharge end of the conditioner. A record of these temperatures is made on the recorder 58 which is connected to suitable thermometer-bulbs in the cooker and conditioner.

My improved process may be used to advantage in the treatment of tung nuts where any access of air to the material in process is extremely undesirable. The feeder 8 when filled with tung nuts substantially prevents any entrance of air into the equipment at this point. The rest of the equipment is operated in a substantially sealed condition keeping the vents on the cooker closed except for the sliding damper 22a which

may be opened slightly, just sufficient to expel the water vapor generated in the cooker without permitting access of air to the interior of the cooker. The short transfer conveyor 25 is also substantially air-tight and is of such short length that no cooling of the material takes place therein which might otherwise cause air to be sucked into the conveyor. The conditioner 5 is operated in a substantially sealed condition with the door 31 closed and with the butterfly damper 51 open only sufficiently to allow the escape of the desired amount of water vapor from the conditioner without access of air to the interior of the conditioner. A very high production of good quality tung oil is achieved by this process.

One advantage of my new process in treating flaxseed or linseed is that the mucilaginous material of the hull is preserved in the linseed meal or cake even though the material is passed through a screw-type press. To my knowledge this has heretofore been regarded as impossible and the linseed meal obtained from a screw press has been granular as compared with the more plastic cake which was produced by the hydraulic type of press. I believe that this improved cake combined with a very high quality and high yield of linseed oil is the result of the slow steeping process at a comparatively low temperature in the large mass of material in the cooker 6 with little removal of moisture, combined with the final removal of moisture in the conditioner and the very close control of the temperature of the product at the discharge end of the conditioner.

My process has been used successfully on de-corticated peanuts, whole cottonseed, babassu nuts, tung nuts, soy beans, flaxseed and palm kernels and other materials. In fact one of the advantages of the process is that it is applicable to a wide range of products merely by varying the temperatures used and the length of time and quantity of material in the cooker 6, so that the process and apparatus are of more or less universal application to all materials.

What I claim is:

1. A process for treating oil bearing proteinaceous material of vegetable origin to express the liquid content therefrom, comprising heating said material for a period of at least 30 minutes at a temperature at least 10 degrees lower than the predetermined optimum oil-expressing temperature for the particular material, immediately thereafter subjecting said material for approximately ten minutes to a conditioning treatment to reduce and stabilize the moisture content, at a temperature higher than the first heating temperature but not higher than said optimum oil-expressing temperature, and, at the conclusion of said conditioning treatment, without substantial loss of time or temperature, subjecting the material to continuous expressing action at said optimum temperature, whereby the oil is expressed therefrom.

2. A process for treating oil bearing proteinaceous material of vegetable origin to express the liquid content therefrom, comprising heating said material for a period of from 30 to 90 minutes at a temperature at least 10 degrees lower than the predetermined optimum oil-expressing temperature for the particular material, immediately thereafter subjecting said material for from 7 to 15 minutes to a conditioning treatment to reduce and stabilize the moisture content, at a temperature higher than the first heating tempera-

ture but not higher than said optimum oil-expressing temperature, and, at the conclusion of said conditioning treatment, without substantial loss of time or temperature, subjecting the material to continuous expressing action at said optimum temperature, whereby the oil is expressed therefrom.

3. A process for treating oil bearing proteinaceous material of vegetable origin to remove oil therefrom, comprising collecting a mass of the material which at any time is in quantity of the order of more than twenty-five times the quantity then undergoing expression, continuously supplying additional material to the mass at an inlet and continuously releasing it therefrom at an outlet at substantially the rate of expression, subjecting the material as it advances in the mass from the inlet to the outlet to a heating treatment with gradual rise of temperature to a maximum value definitely lower than the predetermined optimum oil-expressing temperature for the particular material, then, without substantial loss of temperature or time, subjecting the released material in smaller quantity to a conditioning treatment for a period of shorter duration than the first heating treatment, to reduce and stabilize its moisture content at the optimum value for expressing with a gradual temperature rise to said optimum temperature, and finally, again without substantial loss of time or temperature, subjecting the material to continuous expressing action under said optimum conditions of temperature and moisture content.

4. A process of the character described in claim 3 in which, during the first heating treatment, the temperature is permitted to rise to a maximum value which is approximately 10° F. below the optimum oil expressing temperature.

5. A process of the character described in claim 3, in which a mass of the material is collected which at any time is of the order of more than forty times the quantity then undergoing expression.

6. A process for treating oil-bearing proteinaceous material of vegetable origin to express the liquid content therefrom, comprising heating said material for a period of at least 30 minutes at a temperature at least 10 degrees lower than the predetermined oil-expressing temperature for the particular material, immediately thereafter subjecting said material for approximately 10 minutes to a conditioning treatment to reduce and stabilize the moisture content, at a temperature higher than the first heating temperature but not higher than said predetermined oil-expressing temperature, and, at the conclusion of said conditioning treatment, without substantial loss of time or temperature, subjecting the material to continuous expressing action at said predetermined oil-expressing temperature whereby the oil is expressed therefrom.

FREDERICK W. WEIGEL.
